UNITED STATES PATENT OFFICE.

WILLIAM BYFIELD SHORT, OF NEW YORK, N. Y.

ARTIFICIAL TOOTH FOR CROWNS AND BRIDGES.

No. 825,356.

Specification of Letters Patent.

Patented July 10, 1906.

Application filed April 8, 1905. Serial No. 254,445

To all whom it may concern:

Be it known that I, WILLIAM BYFIELD SHORT, a citizen of the United States, residing at New York, county of New York, and 5 State of New York, have invented certain new and useful Improvements in Artificial Teeth for Crowns and Bridges, of which the following is a full, clear, and exact description.

My invention relates to artificial teeth, and particularly to improvements in crown and bridge work.

It consists, broadly, in the means and method of attaching porcelain faces to backings, the purpose being to provide a construction of the greatest possible strength, which will entirely eliminate the necessity of pins or rivets and which will make it possible to readily renew said porcelains in the event of 20 breakage without the necessity of removing the backing.

The invention is applicable to both anterior and posterior teeth. In the former the exposed or cutting edge of the tooth is porcelain, while in the latter the cusp is also of porcelain. The method of connecting each tooth to its support is such that the strains of occlusion are distributed uniformly over both the porcelain and the backing, so that 30 the danger of breaking or loosening the former is reduced to a minimum. It will be seen also that the method of construction enables the practitioner to apply the tooth in any mouth no matter how close the bite may 35 be. These and other advantages will be apparent to the experienced dentist.

In the drawings, Figure 1 is a front perspective view of a bridge formed of my improved artificial teeth. Fig. 2 is a similar view, the porcelain faces being removed. Fig. 40 3 is a section on the line 3 3. Fig. 4 is a view of the rear side of the porcelain facing shown in Fig. 3 detached. Fig. 5 is a section on the line 5 5. Fig. 6 is a view of the rear side of 45 the porcelain facing shown in Fig. 5 detached.

I will first describe the construction of the tooth shown in Figs. 5 and 6. In these views, 1 is the backing of such form as would be used in a bridge. 2 is the porcelain facing 50 appropriate for the backing 1. 2^a is the rearward extension on the porcelain facing 2. This extension is undercut on opposite sides so as to form a dovetail, and this dovetailed portion is adapted to fit into an oppositely-formed cavity in the face of the backing. The dovetailed extension 2^a, on the rear of the

porcelain facing 2, is of nearly the same width as the extreme width of the tooth and of nearly the height of the face of the backing. The dovetailed extension is also formed integrally with and on the porcelain. The width of the facing at the bottom of the groove formed by the dovetailed extension should be from four to eight times the thickness of the extension. The result is a substantial holding-surface is afforded of such relatively great area that the strains of occlusion are distributed over the entire tooth. The dovetailed extension closely fits the cavity arranged to receive it in the backing 1, and the same is held in by the use of a suitable adhesive material. Because of the expansive area of the dovetailed portion I have found that not only is the tooth capable of withstanding very hard usage, but that by the use of cement alone the facing 2 is firmly held against accidental displacement. As a result of my improvement, it is unnecessary to use any rivets or metallic connecting-pieces.

I am aware that heretofore metallic pins and dovetails have been resorted to; but never heretofore has a construction been provided in which the dovetailed connection was so formed relatively to the area of the tooth and the backing that metallic attaching-pieces, such as pins or rivets, could be successfully eliminated. It has been found that when pins or metallic connecting-pieces are formed with the porcelain facings microscopic fissures occur in the porcelain, which substantially weaken the same and render it liable to break. By my invention this is avoided. Now referring to Figs. 3 and 4, 1^a represents the metallic backing in the form of a crown. 2^b represents the porcelain facing, 95 2^c representing the dovetailed rear portion. In this case, as in the former case, the dovetailed portion is formed integrally with the tooth and of only slightly less area than the rear of said casing. In this case the tooth is represented as an anterior one, and one of the advantages is that the cusp portion may be formed entirely of porcelain. By my arrangement the gold backing is practically invisible, yet reinforces and supports the facing 100 at all vulnerable points. The joint between the backing and the integral extension of the facing comes substantially at the edge of the tooth, so that there is little danger of accidental contact at this point, which would tend to 105 break away the facing.

In Figs. 1 and 2 I have shown a bridge in

which the two end teeth are crowns connected in the usual manner by a metallic backing, all arranged to receive several appropriate porcelain facings. In these views 1^b 1^b are the crown-backings, while 1^c 1^c are the bridging-backings. 2^d 2^d are the facings for the crown-teeth, while 2^e 2^e are the facings for the bridge-teeth.

It should be understood that the drawings are illustrative rather than definitive, save, of course, as to the means of connection.

It will be seen that in all cases the dovetailed portion is integral with the porcelain facing and is of but slightly less area than the rear surface of the same.

What I claim is—

As an article of manufacture, an artificial tooth formed of two permanently-united parts, a metallic backing part having an outwardly-protruding flange with slightly-taper-

ing sides and a connecting top continuous therewith forming a shallow cavity with undercut sides, and a non-metallic facing of porcelain-like material having an extension at the rear of substantially the same width as 25 its main portion and having a shallow groove extending along the sides and a shoulder across the top, the main portion extending above the shoulder, and an adhesive material 30 permanently securing the extension of said facing in the cavity formed by the flanges and top of the backing, the joint between the backing and the facing being substantially at the side edges and across the top of the extension a short distance below the 35 top of the facing.

WILLIAM BYFELD SHORT.

Correction in Letters Patent No. 825,356.

It is hereby certified that in Letters Patent No. 825,356, granted July 10, 1906, upon the application of William Byfeld Short, of New York, N. Y., for an improvement in "Artificial Teeth for Crowns and Bridges," an error appears in the printed specification requiring correction, as follows: In line 100, page 1, the word "casing" should read *facing*; and that the said Letters Patent should be read with this correction therein that the same may conform to the record of the case in the Patent Office.

Signed and sealed this 24th day of July, A. D., 1906.
